UNITED STATES PATENT OFFICE.

JULIUS HAMMESFAHR, OF NEWARK, NEW JERSEY, ASSIGNOR TO THE R. NEUMANN HARDWARE CO., A CORPORATION OF NEW JERSEY.

LOCKING MECHANISM FOR BAG-FRAMES.

1,278,640.

Specification of Letters Patent. Patented Sept. 10, 1918.

Application filed April 12, 1918. Serial No. 228,127.

To all whom it may concern:

Be it known that I, JULIUS HAMMESFAHR, a citizen of the United States, residing at Newark, in the county of Essex and State of New Jersey, have invented certain new and useful Improvements in Locking Mechanism for Bag-Frames; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention has reference, generally, to improvements in bag-frames; and the present invention relates, more particularly, to a novel locking attachment for bag-frames, combining with the hinged frame-sections a lock-actuated and hasp-engaging mechanism, arranged and constructed with a view of dispensing with the additional hasp-engaging bag-frame fasteners mounted upon the outside of one of the frame sections and operated independently of the main hasp-engaging lock.

The present invention, therefore, has for its principal object to provide a novel and simply constructed, as well as an easily actuated and effectively operating hasp-engaging mechanism for bag-frames, combining with the hinged frame-sections, a hasp-engaging lock, and an auxiliary hasp-engaging means, in the form of slides which are actuated simultaneously with the operation of the lock-mechanism, to disengage from their normal holding or locked engagement with an arrangement of auxiliary hasps, and to dispense with the employment of additional bag-frame fasteners mounted upon the outside of one of the frame-sections.

Other objects of the invention not at this time more particularly enumerated will be clearly understood from the following detailed description of the present invention.

With the various objects of the present invention in view, the said invention consists, primarily, in the novel locking-attachment for bag-frames hereinafter more fully set forth; and, the invention consists, furthermore, in the novel arrangements and combinations of the several devices and parts, as well as in the details of the construction of

the said parts, all of which will be more fully described in the following specification, and then finally embodied in the clauses of the claims which are appended to and which form an essential part of the said specification.

The invention is clearly illustrated in the accompanying drawings, in which:—

Figure 1 is a top view of a bag-frame, provided with a locking attachment therefor, made according to and embodying the principles of the present invention, the two bag-frame-sections being represented in a partly opened and unlocked relation, so as to show in connection therewith the arrangement or disposition of the several hasp-lugs; and Fig. 2 is a front face view of the frame-sections and the locking attachment in their closed relation, the usual hinged end-members or portions of the frame-sections being represented as being broken away.

Fig. 3 is a longitudinal vertical section of the outer or main frame-section and the locking attachment connected therewith, the manipulating lock which is employed in connection with said frame-section for actuating the said locking attachment being represented in elevation.

Fig. 4 is a detailed longitudinal vertical section, on an enlarged scale, of a fragmentary portion of the outer or main frame-section, the manipulating lock-mechanism mounted upon said frame-section, and a pair of oppositely movable hasp-lug engaging slides, adapted to be actuated by said lock-mechanism.

Fig. 5 is a top or plan view of a fragmentary portion of the outer or main frame-section, with the lock-mechanism omitted from said view, said view showing in connection therewith, also in top or plan view, portions of the respective slides and casings or shells in which said slides are movably disposed.

Fig. 6 is a bottom view of the lock-casing, with the bottom-plate thereof omitted from said view, said view illustrating the slide-actuating mechanism or devices in their normal initial positions; and Fig. 7 is a similar view of the same devices and parts of the said lock-mechanism, illustrating the relative position of the various parts when actuating the said hasp-lug engaging slides.

Fig. 8 is a plan view of the inner face of

the bottom-plate of the lock, showing in connection therewith a key-operated tumbler pivotally mounted upon said plate, for locking the lock-mechanism against movement.

5 Similar characters of reference are employed in all of the said above described views, to indicate corresponding parts.

Referring now to the several figures of the drawings, it will be seen, that the locking attachment is shown in connection with the class of bag-frames known in the trade as "English" or sewed-in bag-frames, and while in the following specification I have also described the said attachment mounted 10 upon and used with the frame-sections of this type of bag-frames, it will be understood, however, that the locking attachment may be attached to and used also with other styles and types of bag-frames.

20 In the present drawings, the reference characters 1 and 2 indicate the outer members of the respective frame-sections, the frame-section 1 having secured thereto, by means of the usual brackets 3, or other suitable securing means, the usual form of vertically disposed side-member or element 4. In like manner, the frame-section 2 has secured thereto by means of the usual brackets 5, or other suitable securing means, the 25 usual form of vertically disposed side-member 6, the respective leg-members of said side-elements 4 and 6 being operatively connected by means of any usual and well-known hinges, which, however, are not here shown.

30 Suitably secured to the said side-member or element 6, at desired points, and projecting laterally from the inner faces of said side-element 6, are a plurality of hasp-lugs, as 7, 8, 9, and 10, each hasp-lug being provided with a retaining or holding hook 11 with beveled nose 12, substantially as illustrated in Fig. 1 of the drawings, and for the 35 purposes to be presently more fully described.

The lock-mechanism for actuating a pair of oppositely moving hasp-lug engaging slides, to be hereinafter more particularly described, consists, essentially, of a main 40 shell or casing comprising a top or upper face 13 comprising the longitudinally extending side-walls 14 and the end-walls 15, said top or upper face being also provided, if desired, with a key-receiving hole or 45 opening 16 for the purposes to be presently set forth.

Extending from the lower marginal edge-60 portions of said sides 14 are suitably disposed clamping or fastening lugs, as 17, the lower marginal edge portions of the end-walls 15 being also preferably provided with retaining lugs, as 18, although the said latter lugs may be dispensed with, if desired.

Suitably secured over the open bottom of 65 the said lock-casing or shell, by means of the

said several lugs just mentioned is a bottom-plate, as 19, see Fig. 8 of the drawings, said plate being provided with longitudinally extending openings or slots 20 for the reception of the said lugs 17 which are also 70 passed through correspondingly disposed slots 21 in the frame-section 1, and then clamped against the face of the said frame-section, to secure the locking and said inner plate 19 in their fixed positions. When the 75 end-lugs 18 are employed, the said plate 19 is formed with correspondingly placed slots, as 22, with which the said end-lugs 18 register in the manner illustrated more particularly in Fig. 4 of the drawings. Of course 80 it will be fully understood, that any other means may be readily employed for securing the said bottom-plate 19 in its fixed position over the open portion of the said main lock-casing or shell, if desired.

85 As shown more particularly in said Fig. 4 of the drawings, the said bottom plate 19 is made in the form of a shell or casing, having the longitudinally extending side-walls 23 and the end-walls 24, the latter being formed 90 with cut away portions or openings 25 for the purposes hereinafter more fully set forth.

In longitudinal alignment with the said lock-casing or shell and its shell-like bottom-95 plate 19, contiguous to the opposite end-walls 24, are a pair of slide-receiving shells or casings 26 and 27, said shells or casings being suitably secured upon the upper or outer face of the said frame-section 1 by means of the 100 usual clamping lugs 28 and rivets 29, as shown; although it will be fully understood, that any other means of fastening may be employed, if desired.

105 Slidably disposed within the respective shells or casings 26 and 27 are a pair of plates or slides 30, said slides having their end-portions 31 extending from the open-ended portions 32 of the respective shells or casings 26 and 27 and through the cut-away 110 portions or openings 25 into the shell or casing formed by the bottom-plate 19, in the manner illustrated in said Fig. 4 of the drawings. Suitably connected with the respective plates or slides 30, and depending therefrom through properly placed elongated openings or slots 33 in the frame-section 1, are a pair of hasp-lug engaging posts or elements 34 and 35, said posts or elements being movably disposed in said openings or 115 slots 33 and being adapted to be engaged by the retaining or holding hooks 11 of the respective hasp-lugs 9 and 10 when the two frame-sections 1 and 2 are brought into their closed relation.

120 Oscillatory mounted upon the top or upper face 13 of the main lock-casing or shell is a finger piece, as 36, of elongated configuration, so as to conform to the general configuration of the top of said main 125

lock-easing or shell, substantially as shown in Fig. 1 of the drawings, said finger piece being provided with a downwardly extending pivot-post 37, which extends into and through a hole 38 in the said top 13, said hole providing a suitable bearing in which the lower end-portion of said post 37 is oscillatorily disposed. Suitably mounted upon the projecting end-portion of said post 37, 5 within the chamber or hollow part of said main lock-easing or shell is a slide-actuating plate or cam, as 39, said plate in the present case being provided with a pair of studs or projections, as 40 and 41, one of which as 10 41 is adapted to be moved against a stud or stop 42 extending from the inner face of the top 13 of the main lock-easing or shell, for the purpose of arresting, at the proper time, the return movement of the finger-piece and causing it to assume its normal 15 initial position indicated in Fig. 1 of the drawings. Slidably disposed within said main lock-easing or shell and located upon opposite sides of said actuating plate or cam 39, as will be seen from an inspection of Figs. 4, 6 and 7 of the drawings, are a pair of lock-post carrying plates or slides 43 and 44, the slide 43 being formed with longitudinally extending guide-flanges or ribs 20 45 and 46, and the said slide 44 being likewise formed with longitudinally extending guide-flanges or ribs 47 and 48. A coiled spring 49 having its respective ends suitably attached to the respective plates 43 and 44 by means of pins 50, or otherwise, causes 25 certain projections 51 and 52 extending from the respective flanges or ribs 45 and 47 to contact with the respective projections or studs 41 and 40 of the plate or cam 39, substantially as shown and for the purposes to 30 be presently described. As an extra precaution, if desired, the slide 44 may be provided with an end-tongue 53 upon which is mounted the one end of an auxiliary compression spring 54, the other end of said spring being in engagement with the inner face of the one end-wall 15 of the main lock-easing or shell. Connected with and extending downwardly from the said slide 43 is 35 a post 55, said post extending into and being slidably disposed in an elongated opening or slot 56 in the top of the closing plate 19. Said post 55 also extends through a slot 57 in the one plate or slide 30, being snugly fitted in said slot 57, so that the movement of said post 55 will correspondingly move said plate or slide 30, the lower end-portion of the said post 55 extending into and 40 through a correspondingly placed elongated opening or slot 58 in the main frame-section 1 for engagement with the previously mentioned hasp-lug 7 of the frame-section 2, as will be evident. Similarly, there is connected with and extending downwardly from 45 the slide 44 a post 59, said post extending into and being slidably disposed in an elongated opening or slot 60 in the top of the closing plate 19. Said post 59 also extends through a slot 61 in the other plate or slide 30, being snugly fitted in said slot 61, so that the movement of said post 59 will correspondingly move said plate or slide 30, the lower end-portion of said post 59 extending into and through a correspondingly placed elongated opening or slot 62 in the main frame-section 1 for engagement with the other hasp-lug 8 of the frame-section 2, as will be clearly understood.

The various devices and parts of the lock-mechanism can be locked against movement, when desired, by a tumbler, as 63, pivotally mounted upon a pivot-post 64 connected with the bottom-plate 19, as shown, said tumbler having an elongated opening or slot, as 65, through which the post 55 projects, and having an off-set 66 for engagement with said post 55 when a key is inserted through the key-hole 16, mounted upon the key-post 67, and then turned into the receiving portion 68 of the tumbler, so as to move the same in the direction of the arrow α , as will be clearly understood from an inspection of Fig. 8 of the drawings.

Thus, when the lock-mechanism within the main lock-easing or shell has not been locked by means of a key, and the frame-section 2 is closed within the frame-section 1, the hasp-lugs 7 and 8 will be snapped into holding engagement with the respective hasp-engaging posts 55 and 59 of the slides 43 and 44, and the hasp-lugs 9 and 10 will be simultaneously snapped into holding engagement with the hasp-engaging posts or elements 34 and 35 of the respective plates 105 or slides 30.

When it is desired to bring the two frame-sections 1 and 2 into their opened relation, the finger-piece 36 is turned on its pivot, so as to assume the position indicated in dotted outline in Fig. 1 of the drawings, whereby the actuating plate or cam 39 will move the slides 43 and 44 in opposite direction, distending the coils of the spring 49 and compressing those of the spring 54, as will be evident, the hasp-engaging posts 55 and 59 being withdrawn from their holding engagement with the hasp-lugs 7 and 8. At the same time, the movements of said posts 55 and 59 in opposite directions will correspondingly move the two plates or slides 30, so that the posts or elements 34 and 35 will also be withdrawn from their holding or retaining engagement with the respective hasp-lugs 9 and 10, permitting thereby the bag-frame to be opened, as will be clearly evident. As soon as the pressure is released from the fingerpiece, the springs 49 and 54 will return the various parts, which were previously moved, to their normal initial position.

sitions so that the frame-sections can be closed, the various hasp-lug engaging posts being once more snapped into their holding or retaining engagement with the various 5 hasp-lugs of the frame-section 2.

Of course, I am aware that some changes 10 may be made in the general arrangements and combinations of the various devices and parts, as well as in the details of the construction of the said parts, without departing from the scope of the present invention as set forth in the foregoing specification, and as defined in the clauses of the claims which are append thereto. Hence, I do not 15 limit my present invention to the exact arrangements and combinations of the several devices and parts as described in the foregoing specification, nor do I confine myself to the exact details of the construction of 20 the said parts as illustrated in the accompanying drawings.

I claim:

1. In combination with the frame-sections 25 of a bag-frame, hasp-lugs extending from one of said frame-sections, a lock mechanism connected with the other frame-section provided with means adapted to engage with some of said hasp-lugs, a lock-casing in which said mechanism is disposed, a finger- 30 piece pivotally mounted upon said lock-casing, means connected with said finger-piece for actuating said locking mechanism, slides actuated from said lock mechanism, and means connected with said slides adapt- 35 ed to engage with others of said hasp-lugs.

2. In combination with the frame-sections 40 of a bag-frame, hasp-lugs extending from one of said frame-sections, a lock mechanism connected with the other frame-section pro- 45 vided with means adapted to engage with some of said hasp-lugs, a lock-casing in which said mechanism is disposed, a finger-piece pivotally mounted upon said lock-casing, means connected with said fingerpiece 50 for actuating said locking mechanism, slides actuated from said lock mechanism, and hasp-engaging posts extending downwardly from said slides adapted to engage others of 55 said hasp-lugs.

50 3. In combination with the frame-sections of a bag-frame, hasp-lugs extending from one of said frame-sections, a lock-casing mounted upon the other frame-section, oppositely moving slides within said lock-casing, hasp-lug engaging posts depending 55 from said slides adapted to engage with some of said hasp-lugs, a fingerpiece pivotally mounted upon said lock-casing, means connected with said fingerpiece for actuating 60 said slides, a second set of oppositely moving slides actuated from the posts connected with said first-mentioned slides, and means connected with said second-mentioned slides adapted to engage with others of said hasp- 65 lugs.

4. In combination with the frame-sections of a bag-frame, hasp-lugs extending from one of said frame sections, a lock-casing mounted upon the other frame-section oppositely moving slides within said lock-casing, 70 hasp-lug engaging posts depending from said slides adapted to engage with some of said hasp-lugs, a fingerpiece pivotally mounted upon said lock-casing, means connected with said fingerpiece for actuating 75 said slides, a second set of oppositely moving slides actuated from the posts connected with said first-mentioned slides, and hasp-engaging posts extending downwardly from said second-mentioned slides adapted to en- 80 gage with others of said hasp-lugs.

5. In combination with the frame-sections of a bag-frame, hasp-lugs extending from one of said frame-sections, a lock-casing mounted upon the other frame-section, op- 85 positely moving slides within said lock-casing, hasp-lug engaging posts depending from said slides adapted to engage with some of said hasp-lugs, a fingerpiece pivot- 90 ally mounted upon said lock-casing, a cam- plate connected with said fingerpiece for actuating said slides, a second set of oppositely moving slides actuated from the posts connected with said first-mentioned slides, and means connected with said second-mentioned slides adapted to engage with others of 95 said hasp-lugs.

6. In combination with the frame-sections of a bag-frame, hasp-lugs extending from one of said frame-sections, a lock-casing 100 mounted upon the other frame-section, op- positely moving slides within said lock-casing, hasp-lug engaging posts depending from said slides adapted to engage with some of said hasp-lugs, a fingerpiece pivot- 105 ally mounted upon said lock-casing, a cam- plate connected with said fingerpiece for actuating said slides, a second set of oppo- sitely moving slides actuated from the posts connected with said first-mentioned slides, and hasp-engaging posts extending down- 110 wardly from said second-mentioned slides adapted to engage with others of said hasp-lugs.

7. In combination with the frame-sections of a bag-frame, hasp-lugs extending from one of said frame-sections, a lock-casing mounted upon the other frame-section, op- 115 positely moving slides within said lock-casing, hasp-lug engaging posts depending from said slides adapted to engage with some of said hasp-lugs, a spring connecting said slides, and a second spring mounted between the end of one of said slides and an end-wall of said lock-casing, a finger-piece 120 pivotally mounted upon said lock-casing, means connected with said fingerpiece for actuating said slides, a second set of oppo- sitely moving slides actuated from the posts connected with said first-mentioned slides, 125 and a second spring mounted between the end of one of said slides and an end-wall of said lock-casing, a finger-piece pivotally mounted upon said lock-casing, means connected with said fingerpiece for actuating said slides, a second set of oppo- sitely moving slides actuated from the posts connected with said first-mentioned slides, 130

and means connected with said second-mentioned slides adapted to engage with others of said hasp-lugs.

8. In combination with the frame-sections 5 of a bag-frame, hasp-lugs extending from one of said frame-sections, a lock-casing mounted upon the other frame-section, oppositely moving slides within said lock-casing, hasp-lug engaging posts depending 10 from said slides adapted to engage with some of said hasp-lugs, a spring connecting said slides, and a second spring mounted between the end of one of said slides and an end-wall of said lock-casing; a finger-piece 15 pivotally mounted upon said lock-casing, means connected with said finger-piece for actuating said slides, a second set of oppositely moving slides actuated from the posts connected with said first-mentioned slides, 20 and hasp-engaging posts extending downwardly from said second-mentioned slides adapted to engage with others of said hasp-lugs.

9. In combination with the frame-sections 25 of a bag-frame, hasp-lugs extending from one of said frame-sections, a lock-casing mounted upon the other frame-section, oppositely moving slides within said lock-casing, hasp-lug engaging posts depending 30 from said slides adapted to engage with some of said hasp-lugs, a spring connecting said slides, and a second spring mounted between the end of one of said slides and an end-wall of said lock-casing, a fingerpiece 35 pivotally mounted upon said lock-casing, a cam-plate connected with said fingerpiece for actuating said slides, a second set of oppositely moving slides actuated from the posts connected with said first-mentioned 40 slides, and means connected with said second-mentioned slides adapted to engage with others of said hasp-lugs.

10. In combination with the frame-sections 45 of a bag-frame, hasp-lugs extending from one of said frame-sections, a lock-casing mounted upon the other frame-section, oppositely moving slides within said lock-casing, hasp-lug engaging posts depending 50 from said slides adapted to engage with some of said hasp-lugs, a spring connecting said slides, and a second spring mounted between the end of one of said slides and an end-wall of said lock-casing, a fingerpiece 55 pivotally mounted upon said lock-casing, a cam-plate connected with said fingerpiece for actuating said slides, a second set of oppositely moving slides actuated from the posts connected with said first-mentioned 60 slides, and hasp-engaging posts extending downwardly from said second-mentioned slides adapted to engage with others of said hasp-lugs.

11. In combination with the frame-sections 65 of a bag-frame, hasp-lugs extending from one of said frame-sections, a cham-

bered bottom-plate mounted upon the other frame-section, said bottom-plate being provided with elongated openings in its top and having open end-portions, a lock-casing mounted upon said bottom-plate, oppositely 70 moving slides within said lock-casing, hasp-lug engaging posts depending from said slides into and through the elongated openings in said bottom-plate and adapted to engage with some of said hasp-lugs, a spring 75 connecting said slides, and a second spring mounted between the end of one of said slides and an end-wall of said lock-casing, a finger-piece pivotally mounted upon said lock-casing, means connected with said finger-piece for actuating said slides, a second set of slides mounted upon the last-mentioned frame-section, said slides having end-portions extending into and through the open end-portions of the chambered bottom-plate, 80 the end-portions of the said second-mentioned slides being provided with elongated openings into and through which the hasp-lug engaging posts of the first-mentioned slides extend for actuating said second-mentioned slides, and means connected with said second-mentioned slides adapted to engage 85 with others of said hasp-lugs.

12. In combination with the frame-sections 90 of a bag-frame, hasp-lugs extending from one of said frame-sections, a chambered bottom-plate mounted upon the other frame-section, said bottom-plate being provided with elongated openings in its top and having open end-portions, a lock-casing 95 mounted upon said bottom-plate, oppositely moving slides within said lock-casing, hasp-lug engaging posts depending from said slides into and through the elongated openings in said bottom-plate and adapted to engage with some of said hasp-lugs, a spring connecting said slides, and a second spring mounted between the end of one of said slides and an end-wall of said lock-casing, 100 a fingerpiece pivotally mounted upon said lock-casing, means connected with said finger-piece for actuating said slides, a second set of slides mounted upon the last-mentioned frame-section, said slides having end-portions extending into and through the 105 open end-portions of the chambered bottom-plate, the end-portions of the said second-mentioned slides being provided with elongated openings into and through which the hasp-lug engaging posts of the first-mentioned slides extend for actuating said second-mentioned slides, and hasp-engaging 110 posts extending downwardly from said second-mentioned slides adapted to engage with others of said hasp-lugs.

13. In combination with the frame-sections 115 of a bag-frame, hasp-lugs extending from one of said frame-sections, a chambered bottom-plate mounted upon the other frame-section, said bottom-plate being pro- 120

vided with elongated openings in its top and having open end-portions, a lock-casing mounted upon said bottom-plate oppositely moving slides within said lock-casing, hasp-lug engaging posts depending from said slides into and through the elongated openings in said bottom-plate and adapted to engage with some of said hasp-lugs, a spring connecting said slides, and a second spring 10 mounted between the end of one of said slides and an end-wall of said lock-casing, a fingerpiece pivotally mounted upon said lock-casing, a cam-plate connected with said fingerpiece for actuating said slides, a second set of slides mounted upon the last-mentioned frame-section, said slides having end-portions extending into and through the open end-portions of the chambered bottom-plate, the end-portions of said second-mentioned 20 slides being provided with openings into and through which the hasp-lug engaging posts of the first-mentioned slides extend for actuating said second-mentioned slides, and means connected with said second-mentioned slides adapted to engage with others of said hasp-lugs.

14. In combination with the frame-sections of a bag-frame, hasp-lugs extending from one of said frame-sections, a chambered bottom-plate mounted upon the other frame-section, said bottom-plate being provided with elongated openings in its top and having open end-portions, a lock-casing

35 mounted upon said bottom-plate, oppositely moving slides within said lock-casing, hasp-lug engaging posts depending from said slides into and through the elongated openings in said bottom-plate and adapted to engage with some of said hasp-lugs, a spring 40 connecting said slides, and a second spring mounted between the end of one of said slides and an end-wall of said lock-casing, a fingerpiece pivotally mounted upon said lock-casing, a cam-plate connected with said fingerpiece for actuating said slides, a second set of slides mounted upon the last-mentioned frame-section, said slides having end-portions extending into and through the open end-portions of the chambered bottom-plate, the end-portions of said second-mentioned 50 slides being provided with openings into and through which the hasp-lug engaging posts of the first-mentioned slides extend for actuating said second-mentioned slides, and hasp-engaging posts extending downwardly from said second-mentioned slides adapted to engage with others of said hasp-lugs.

55 In testimony, that I claim the invention set forth above I have hereunto set my hand 60 this fifth day of April, 1918.

JULIUS HAMMESFAHR.
